HUGH E. SHEDD, OF RED WING, MINNESOTA, ASSIGNOR TO RACINE PAPER
GOODS CO., OF RACINE, WISCONSIN.

DESIGN FOR A MULTIPLE WRAPPER.

SPECIFICATION forming part of Design No. 33,116, dated August 28, 1900.

Application filed June 18, 1900. Serial No. 20,598. Term of patent 7 years.

To all whom it may concern:

Be it known that I, HUGH E. SHEDD, a citizen of the United States, residing at Red Wing, in the county of Goodhue and State of Minnesota, have invented and produced a certain new and useful Design for a Multiple Wrapper; and I do hereby declare the following to be a full, clear, and exact description of the invention, such as will enable others skilled in the art to which it appertains to make and use the same.

This invention relates to a new and useful design for a wrapper adapted to receive cigars and other articles; and the object of the invention is to provide a multiple wrapper having certain distinguishing features.

Referring to the accompanying drawings, Figure 1 is a face view of the new article of manufacture. Fig. 2 is an edge view thereof.

The article of manufacture is of a general oblong or rectangular form, having the front and rear walls *c c* connected together along one edge of the article. Said walls are divided into parallel panels or strips by the elongated

slits *d*, said panels being connected together 25 by the separated bridges between the slits.

a indicates tubes projecting beyond the wall *c* at the ends of said panels between said lines of slits *d*.

b is the creased or lined edge of an end 30 tube *a*.

The essential feature of the design consists of the oblong or rectangular article, having its wall divided into panels by the elongated slits *d* and the projections *a* between the 35 panels and separated by said elongated slits.

Having thus fully described my invention, what I claim as new, and desire to secure by Letters Patent of the United States, is—

The design for a multiple wrapper, substantially as shown and described.

In testimony whereof I affix my signature in presence of two witnesses.

HUGH E. SHEDD.
